BOOK HANGER

Filed Dec. 9, 1929

INVENTOR:
GUSTAV A. SCHWARTZEL

BY Harry A. Beimes

ATTORNEY.

UNITED STATES PATENT OFFICE

GUSTAV A. SCHWARTZEL, OF ST. LOUIS, MISSOURI

BOOK HANGER

Application filed December 9, 1929. Serial No. 412,773.

My invention has relation to improvements in book hangers, that is, devices that may be quickly attached to a book of reference such as a catalog or telephone book for the purpose of suspending the book from a hook for easy access. The invention consists in the novel features of construction more fully set forth in the specification and pointed out in the claims.

The object of the invention is to provide a hanger that may be quickly attached to and detached from the book, one that will not damage the book, and one that is simple but positive in its operation. Further and other advantages will be better apparent from a detailed description of the invention in connection with the accompanying drawings, in which—

Fig. 1 is a perspective view of a book suspended by means of my improved hanger; Fig. 2 is a side elevation of the hanger in operative position with a part broken away; Fig. 3 is a cross-sectional detail taken on the line 3—3 of Fig. 2; and Fig. 4 is a side elevation of the hanger with its cooperative members in open or inoperative position.

Referring to the drawings, H represents my improved hanger comprising cooperative components 1 and 2 pivotally connected by means of a hollow rivet 3 serving as a hinge. The component 1 is U-shaped in cross-section (Fig. 3), and the sides a, a thereof are both provided with tapering slots b, b which are narrower at their closed ends c and flare outwardly at their open ends d. The component 2 is essentially a blade hinged at its lower end, as above described, to the member 1 between the sides a, a thereof, the part of said blade adjacent the hinge 3 being widened inwardly to form a cam 4, and the upper part of the blade being widened to form a handle 5 in which is the opening or eye 6 for receiving a hook 7 from which a book B, engaged by my hanger H, may be suspended. The blade 2 is of a thickness that it will just enter the space s between the sides a, a of component 1. It will be observed that the sides of the cam 4 are slightly beveled as shown at e, e (Figs. 2 and 3) for the purpose of more readily forcing the back f of the book

B into the space s and tightly gripping the same when the components 1 and 2 of the hanger are in operative or closed position. To prevent said components 1 and 2 from being easily separated, a hole 9 is provided in the blade 2 and the metal 1 of the walls a is punched inwardly to provide a detent 8 which enters the hole 9 when the components 1 and 2 are in closed position. When it is desired to release the hook B from the hanger H, the component 2 is merely swung to open position (as shown in Fig. 4) so that the cam 4 will release the back f of the book whereupon the back will easily slip out of the slot b.

Having described my invention, I claim:

1. A book hanger comprising a U-shaped component and a blade component hinged between the sides of said U-shaped component, said sides having open slots to receive the back of the book, and permit the sides to enter between the sheets thereof means on the blade component for cooperating with the slots of the U-shaped component to grip said book back when the components are in closed position and a handle at one end of the blade.

2. A book hanger comprising a U-shaped component and a blade component hinged between the sides of said U-shaped component, said sides having open slots to receive a part of the book, a cam on the blade component adapted to cooperate with the slots on the U-shaped component to grip said book part when the components are in closed position and a handle at one end of the blade.

3. A book hanger comprising a U-shaped component and a blade component hinged between the sides of said U-shaped component, said sides having open slots to receive a part of the book, means on the blade component for cooperating with the slots of the U-shaped component to grip said book part when the components are in closed position, means for holding the components in closed position and a handle at the upper end of the blade.

4. A book hanger comprising cooperative components, one of which comprises a holding sheath having sides in closely spaced relation, the other component comprising a

blade pivotally mounted between the sides of the sheath and receivable therein, alining longitudinally disposed slots in the sides of the sheath adapted to be traversed by a part of the book, and means on the blade for gripping the book part when the blade is housed in the sheath.

In testimony whereof I hereunto affix my signature.

10   **GUSTAV A. SCHWARTZEL.**
